FIG. 3.

Inventor
Charles C. Whelan,
by W. G. Sharpbridge
his Attorney.

UNITED STATES PATENT OFFICE.

CHARLES C. WHELAN, OF WASHINGTON, DISTRICT OF COLUMBIA.

SIGN.

SPECIFICATION forming part of Letters Patent No. 634,316, dated October 3, 1899.

Application filed October 26, 1898. Renewed July 6, 1899. Serial No. 722,978. (No model.)

To all whom it may concern:

Be it known that I, CHARLES C. WHELAN, a citizen of the United States, residing at Washington, in the District of Columbia, 5 have invented certain new and useful Improvements in Signs; and I do hereby declare the following to be a full, clear, and exact description of the invention, such as will enable others skilled in the art to which it appertains 10 to make and use the same.

This invention relates to signs.

The object of the invention is to provide a sign or signs which will not only attract the attention of customers or patrons, but will be 15 attractive and pleasing to the general public.

According to my invention I associate with the merchandise or substance to be sold a movable sign or series of such signs of such character as to give animated or animated 20 and sparkling effects.

The invention consists in the combination of a suitable support, one or more movable display cards or signs attached to said support, a means for forcing air, and a trunk or 25 conduit for conducting an air-current from said means to the movable sign.

The invention further consists in certain combinations hereinafter fully described, and particularly pointed out in the claims ap- 30 pended hereto.

In the drawings, Figure 1 is an elevation showing one application of my invention. Fig. 2 is a section on the line 2 2 of Fig. 1. Fig. 3 is a detail showing a terminal of the 35 air trunk or conduit.

In the form in which I have illustrated my invention, 1 represents the glass or transparent part of a show-window. Within this window I have provided a tank 2, within 40 which sea food for customers is exhibited. The sea food may be fish, lobsters, oysters, crabs, and the like. In lieu of the tank, however, shelves or display-stands for any character of merchandise may be substituted, the 45 signs or display-cards being made to correspond with the merchandise exhibited in the window. I also arrange in the window a suitable frame or support 3 of ornamental or attractive character and suspend from this 50 frame display cards or signs 4 of any suitable or attractive character. I contemplate, however, using highly-polished glass the

ground of which is colored or stained and the lettering upon which is plain transparent glass. The display-cards may be of any 55 suitable or desired substance other than glass, if so desired; but by the use of beveled plate-glass or cut-glass panels I am enabled, in connection with a proper light, to obtain sparkling effects and through the air-blast, which 60 gives a movement to these panels, obtain animated effects. Leading from any suitable source of air under pressure, as a fan 5, is an air trunk or conduit 6 for directing a current of air against one or more of the display-cards.

In the form of apparatus which I have adopted for illustrating this application the trunk is provided with branches 7 7, through which a blast or current of air is directed to 70 the side of the signs 4 4, so as to give said signs or display-cards a vibratory or swinging movement. The trunk 6 has a somewhat reduced continuation 8, extending past the signs or display-cards 4 4 and up to about the 75 top of the frame 3. Leading from the upper part of this continuation are branches 9 9, arranged to discharge currents of air on opposite sides of a pennant or streamer 10. This streamer is removably supported in a socket 80 in or connected with the upper end of the continuation 8 of the air-trunk and is firmly held in position by means of set-screw 11. In this way the pennant or streamer will be kept agitated or caused to wave constantly during the 85 continuation of the blast. The pennant or streamer may also be readily removed and replaced by another to correspond with the varying products or articles exhibited for sale. In some instances it may be desirable to throw 90 the pennant or streamer out of the plane of the frame or the stem of the air-trunk. I therefore provide a crooked extension or continuation of the main trunk, as shown in Fig. 3 of the drawings. I have illustrated in connection with my sign system an electric light 95 and reflector 12 for illuminating the window and the display-signs.

The staff of the pennant or streamer terminates with an ornamental head 13, provided 100 with a notched top to hold by friction a card or sign 14, which may be removed from time to time and another of different character substituted therefor. The head 13, as shown

in the drawings, is made spherical in form; but obviously any ornamental configuration may be adopted for this purpose, or, indeed, the staff itself may be notched, leaving the top of the staff plain.

Having described my invention, what I claim as new, and desire to secure by Letters Patent, is—

1. A sign embracing the combination of a pennant or streamer, means for producing an air-blast, a single trunk or conduit leading from source of air-blast, having branches for discharging currents of air on opposite sides of the pennant, substantially as described.
- 15 2. A sign embracing the combination of a plurality of independently-movable signs or display-cards, a blower, a trunk or conduit leading from the blower, and branches leading from the trunk to discharge air-currents against the face of the display-cards, substantially as described.
- 20 3. A sign embracing the combination of a pennant or streamer, a blower, an air trunk or conduit leading from blower, and branches leading from air-trunk to direct currents of

air on opposite sides of the streamer, substantially as described.

4. A sign embracing the combination of a plurality of suspended display cards or signs, a pennant or streamer, a blower, a trunk or conduit leading from blower, branches leading from the trunk toward the face of the display-cards, and branches leading from the trunk to the opposite sides of the pennant, substantially as described.

35 5. A sign involving the combination of means to display merchandise or articles to be sold, movable signs or display-cards associated with such means, a blower, an air-trunk leading from blower, and branches leading from the air-trunk for directing currents of air against the face of the signs, substantially as described.

40 In testimony whereof I affix my signature in presence of two witnesses.
